CLAIM

The ornamental design for a footwear upper as shown and described.

DESCRIPTION

FIG. 1 is a perspective view of a footwear upper embodying the new design;

FIG. 2 is a top view thereof;

FIG. 3 is a bottom view thereof;

FIG. 4 is a right side view thereof;

FIG. 5 is a left side view thereof;

FIG. 6 is a front view thereof; and,

FIG. 7 is a rear view thereof.

The figures show features in of an article of footwear with dash-dash broken lines that form no part of the claimed design. Further, the dash-dash broken lines immediately adjacent the portions shown in solid lines form the boundary of the design, with the dash-dash broken lines forming no part of the claimed design. The even length broken lines in the figures depict stitching, which forms no part of the claimed design.

1 Claim, 7 Drawing Sheets
